UNITED STATES PATENT OFFICE.

EDWARD A. DUNN, OF NEWTON, MASSACHUSETTS.

FILE.

1,081,727.

Specification of Letters Patent. Patented Dec. 16, 1913.

Application filed September 14, 1910, Serial No. 581,982. Renewed April 22, 1913. Serial No. 762,936.

To all whom it may concern:

Be it known that I, EDWARD A. DUNN, of Newton, in the county of Middlesex and State of Massachusetts, have invented certain new and useful Improvements in Files, of which the following is a specification.

The object of the present invention is to provide a file or folder adapted to hold papers relating to certain persons or matters 10 in a filing case or drawer.

The object of the invention is to strengthen or stiffen such a folder at the point where the identification name or symbol of the file is applied, without increasing the weight or 15 thickness of the file as a whole in the least, thereby enabling a folder to be made as a whole of relatively light and thin stock, while being at the same time greatly strengthened at the portion where the name 20 or symbol occurs and where the folder is most frequently grasped and handled.

Another object is to make the edge of the folder or file which is subjected to handling rounded and smooth, merging gradually 25 with the faces of the stock on a continuous curve, instead of presenting raw edges and sharp corners.

In the accompanying drawings I have illustrated various forms in which the invention 30 may be embodied, these forms all having the same essential principle.

Figure 1 represents one form of the file or folder in which the reinforcement is made by folding over the edge of the back of the 35 folder and pasting down the flap thus formed against the back. Fig. 2 represents a third form in which the back of the folder is reinforced at its edge in the manner shown in Fig. 1, and is cut to provide a tab. Fig. 3 40 represents a fourth form in which the back of the folder is reinforced only at the tab. Fig. 4 represents the blank from which the form shown in Fig. 3 is made.

The same reference characters indicate the 45 same parts in all the figures.

The article to which the invention relates is the folder or file commonly used in business to preserve all the papers relating to certain particular matters together. Such 50 folders are generally made of material having the necessary qualities of toughness and stiffness, such as Manila paper. The folder as a whole is represented by *a* and the back or rear leaf thereof by *b*. This back is 55 longer or higher than the front leaf either throughout its entire width, or for a limited

extent. The projecting part of the back is adapted to bear the name of the person or of the matters to which the contents of the file relate. This part of the folder is subjected to a much greater amount of handling than any other part, particularly in the course of searching through a cabinet for any particular file tucked between others, and it is the purpose of this invention to reinforce 60 such part locally. In the form shown in Fig. 1 this reinforcement is made by providing the back of the folder with a flap *c* which is doubled against the back and pasted down. The vertical extent of the flap is 65 relatively slight as compared to the entire height of the file, and preferably is such that when the file is empty and closed the front leaf will not overlap it, whereby it does not increase the thickness of the file in the 70 slightest. Thus the file is given more than double strength in the part where strength is most needed, without requiring the use of heavy stock.

In Fig. 2 the back *b'* is provided with a 75 tab *d'*, which is reinforced by a flap *e'*. The latter is made in one piece with the back, and is doubled over against the same and pasted. The dotted line *f* represents the original line of fold. After the flap is thus 80 secured the folded edge of the back is cut away, as represented in full lines in Fig. 2, leaving only the tab to project above the front leaf, this tab and the entire upper portion of the back being, however, strength- 85 ened and reinforced by the flap.

In Fig. 3 the folder is provided with reinforcement only at and adjacent to the tab. Here the reinforcement consists of a flap *g*, which, when the blank for the folder is cut, 90 extends beyond a tab *h*. When the tab is folded over upon the dotted line *i* shown in Fig. 4, a reinforced tab integral with the folder back, and having an integral reinforcement, is made, as shown in Fig. 3. 100

In each embodiment of the invention the reinforcement is wholly above either the majority of papers in the file, or the front of the file as well. Thus I am enabled to use the thinnest stock having enough stiffness to 105 enable it to stand upright when placed on edge, and, at the same time reinforce the portion subjected to the greatest handling and hardest usage in a manner such as to give it two-fold strength. By this means I 110 can provide files having as great strength for all practical purposes as files made of

twice as heavy and bulky stock, but occupying only half the space. From a practical standpoint this is of great importance, in that it economizes space in filing cabinets 5 and enables the cost of the file wrappers to be greatly reduced.

The manner of applying the name, number, or other symbol on the file may be anything desired. For instance, the symbol 10 may be stamped or marked directly on the tab or edge, as shown in Fig. 1, or it may be made on a label pasted thereto, or it may be applied on the surface of the folder back, as shown in Figs. 2 and 3, being made 15 visible through an opening left in the reinforcing flap.

It will be noted that whether the entire 20 upper edge of the folder back, as shown in Fig. 1, or the upper edge of the tab, as shown in Figs. 2, 3 and 4, is made by folding over a part of the stock, such edge is smooth and rounded, merging with the front and rear surfaces of the folder back on a smooth curvature instead of being divided 25 therefrom by sharp corners. Thus such edge, which is the part subjected to handling when the files are being looked over in a case, is protected in the fullest possible manner against wear. It is obvious that where 30 the back edge is cut and so presents a raw edge, the wear is greater than when the edge is rounded by folding over a part of the stock of which the file is formed. At the same time the thickness of the file is not 35 increased. The part of the back edge which is folded over is made to adhere permanently to the folder back, as previously mentioned, hence the edge to which attention has just been called is not subjected to back 40 and forth bending with consequent liability of breaking and tearing, such as would be the case if the folded-over part or flap were not thus permanently and adherently united to the back of the file.

45 I claim,—

1. A file wrapper or folder having a back, an integral edge portion of such back being folded flat against the back, whereby a

transversely rounded extreme edge of double thickness is provided, the entire folded edge 50 portion being adherently secured to the said back, whereby the said wrapper or folder is not only permanently reinforced, but the rounded form of the extreme edge is maintained, and the front being shorter than the 55 back to such an extent that its upper edge may lie beneath the bottom of the folded over portion when the folder is empty and closed, whereby to make the folder of uniform thickness from top edge to bottom. 60

2. A file wrapper or folder having a front and a back, and a flap integral with the upper edge of the back folded flat against the back and pasted thereto, the front being shorter than the distance between the 65 lower edge of the flap and the bottom of the folder, whereby to lie under the flap when the folder is empty and closed.

3. A file wrapper or folder having a back, and a flap integral with the upper edge of 70 the back folded flat against the back and pasted thereto, said flap having an aperture through which a name or other indication applied to the back may be seen.

4. A file wrapper or folder including 75 front and back leaves, the back leaf having a projecting tab formed integrally with the back and reinforced by an integral extension of the back doubled over at the top edge of the tab and pasted to the back. 80

5. A wrapper or folder having a back, an integral extension of such back being folded against the back and permanently secured thereto by an adhesive, a part of the upper folded edge of the back being cut away 85 and leaving a projecting tab, the outer edge portion of which is transversely rounded, and the tab being thereby formed integral with the back and of double thickness. 90

In testimony whereof I have affixed my signature, in presence of two witnesses.

EDWARD A. DUNN.
